UNITED STATES PATENT OFFICE.

ROGER A. SIMONSON, OF EVANSTON, ILLINOIS.

UTILITY ROOM FOR HOSPITALS AND THE LIKE.

Application filed December 10, 1924. Serial No. 754,881.

This invention relates to improvements in the arrangement and equipment of hospital rooms, and more particularly to the method and means for dividing off and enclosing 5 a part of the room into a separate utility room, including the toilet fixtures, cabinets, closets, etc., so that the nurse or attendant may have complete privacy from the patient or others that may be in attendance.

10 The average patient's room of the modern hospital is admittedly deficient in the provision of suitable accommodation for the nurse in cases of such a nature that one in constant attendance is required. Hence, it 15 is the object of the present invention to provide a portable utility enclosure or auxiliary room which may be built or erected in the room to be served thereby.

20 A preferred embodiment of the invention is disclosed in the accompanying drawings in which,

25 Figure 1 is a view in horizontal section showing the preferable location and arrangement of the utility room, and showing one arrangement of the partition walls.

Figure 2 is a view similar to Figure 1, showing another arrangement or division of the space enclosed by the room.

30 Figure 3 is a view in vertical section taken on line 3—3 of Figure 2, and

Figure 4 is a view in vertical section taken on line 4—4 of Figure 2.

35 For the purpose of disclosing the structure of the invention it may be assumed that the installation is to be made in the average sized hospital room opening into a corridor through a hinged door or entrance A, the dimension of the room being such that its length, measured at right angles to the corridor, exceeds its width.

40 Structurally, the utility room is a sheet metal enclosure, with walls, ceilings, doors, cabinets, shelves, locker, wash bowl and other fixtures forming an integral and self contained unit, having only a floor in common with the room in which it is erected. The utility room is placed adjacent the entrance end of the hospital room and closes up the space in front of and on one or both sides 45 of the entrance A. As disclosed herein, the utility room has an open door-way A¹ surrounded by a metal jamb 1, which bears flush around the frame of the corridor entrance door A, so that the latter serves to close both the patient's room and the utility room from the outside. The door-way oc-

cupies practically one half of the front wall, the remaining front wall section 2 extending parallel with the corresponding front wall 3 of the room and spaced a short distance from it, and forms one wall of the toilet compartment partially identified by a towel rack 4 mounted thereon. Joining the front wall section 3 is a vertical end wall 5, extending into the patient's room at right angles and spaced from the adjacent side wall of the room. Recessed into this wall are two cabinets 6, 6, consisting of metal side, bottom and top walls, projecting rearwardly beyond the plane of the wall. These 60 cabinets are equipped with swinging doors 7 with a mirror in one or both. The cabinets extend halfway down from the top of the room, and are equipped with shelves, and other conveniences. Just below the cabinets is another recess extending the full width of the wall, its bottom surface serving as a shelf 8. The wall space below the shelf is available for the mounting of the wash bowl 9, and various other fixtures, and 70 through which extend the several water and plumbing connections for the fixtures which are mounted upon or close to this wall. The opposite end wall 10, is immediately adjacent the entrance A¹ and is a plain 75 metal panel except for a full height locker 11, with metal side, rear and top walls recessed into the wall and provided with a hinged door 12, as clearly shown in Figure 4.

80 The remaining side wall, opposite the entrance to the room, consists of sections or panels, constructed as follows: Immediately adjacent the end wall 4, and at the end enclosing the toilet fixtures, is a door 13, 85 hinged along the side nearest the end of the room and preferably to swing outwardly. This door is hung in a metal frame of the usual construction, the portion of the frame along its forward edge being a stationary 90 mullion 14, which is located opposite the left side of the entrance doorway A¹. Hinged to the mullion is a swinging wall panel or section 15, which in turn has hinged to its outer edge a door 16, the combined width 95 of the wall section 15 and door 16, being equal to opening between the mullion 14, and the edge of the opposite or right hand side wall 10. Moreover, the combined width 100 of these sections is equal to the width of 110 the enclosure as will presently be seen.

Over the entire enclosure is a top wall or

ceiling 17, elevated but a short distance above the tops of the doors, so that the height of the utility room is somewhat less than the height of the room in which it is 5 installed. The ceiling may be perforated or grilles to provide for ventilation, fans being used for the purpose, if necessary.

It is to be understood that the structural details of the room is a matter of design and 10 application of approved methods of fabricating sheet metal structures of this character,—thus, where door jambs and stops are required, the door frames would be shaped to provide these members, similarly locks, 15 door knobs, spring latches, and the like, would be provided wherever necessary. For instance, a latch would be provided along the upper edge of the hinged wall section 13, to hold it against movement, as well as a 20 suitable rail or jamb to prevent the same from swinging beyond the straight line position in which it is shown in Figure 2. The doors, 13 and 16, however, are hung so as to open, close, and latch in the usual manner, 25 the former outwardly, as already noted, and the latter inwardly, for the reason presently to be pointed out.

Referring first to Figure 1, it will be observed that the wall section 15, and the door 30 16, have been swung as a single unit transversely across the room. In this position the end of the room containing the toilet fixtures is completely closed off and forms what may be designated as the toilet compartment B, 35 which may be entered either through the door 13, from the interior of the patient's room or from the open passage C, formed between the section 15 and the opposite side wall 10, and leading from the corridor entrance into the larger room. In this way 40 complete privacy is afforded either the patient or the attendant from other occupants of the room, and those persons coming into and going from the room.

45 Considering further Figure 2 it will be seen that the wall section 15, and door 16, have been swung across the inner side wall in which position they were originally described. In this position the toilet compartment B and passage C are thrown into one large compartment D, which serves as a dressing room as well as sleeping room for the nurse or attendant, with access to the locker 11, and by locking the entrance door 50 A, complete privacy is obtained.

Ordinarily, the complete shutting off of the compartment D is for short durations only and hence the patient's room would be accessible at other times through the corridor door A and the inner door 16. The advantage of this arrangement, aside from providing a private dressing compartment for the attendant, is to form a vestibule in which 55 consultations may be held without being overheard, or routine operations carried on

without disturbing the patient. Furthermore, it shuts off the patient from the noise and confusion in the corridor by the presence of an additional partition.

Manifestly, an all-metal enclosure of this 70 character may be designed either for installation in hospitals already erected or to be erected, with the same attendant advantages, that it can be installed as a unit at much less cost than ordinary building construction, 75 besides being fire proof and more sanitary. The chief advantage, however, of the utility room installation is the economical and efficient utilization of space, which is readily appreciated when it is observed that it combines in a single room, the patient's room and lavatory, as well as like accommodations and conveniences for the nurse, with complete privacy for both.

I claim as my invention:

85 1. An article of manufacture for use in a hospital room or the like, having an entrance doorway thereto, comprising side walls adapted to be located wholly within the hospital room and independently of the 90 walls and ceiling thereof, one of said side walls having an opening adapted to register with said doorway, and the opposite side wall having a doorway and a door therein adapted to be swung from a position to close said doorway to a position to close off a portion of said utility room and to provide a through passageway from said entrance doorway to the interior of said 95 hospital room beyond.

100 2. An article of manufacture for use in a hospital room or the like, having an entrance doorway thereto, comprising walls completely enclosing a portion of the space within said hospital room, one of said walls 105 having an opening near one end thereof adapted to register with said entrance doorway, and a correspondingly located doorway in the opposite wall, a door in said last mentioned doorway normally closing off said utility room from the interior of said hospital room and adapted to be swung in another position at right angles to its closed position to shut off a portion of said utility room from the hospital room and to form with another wall a through passage from said entrance doorway into the hospital room.

115 3. An article of manufacture for use in a hospital room, or the like, having an entrance doorway thereto, comprising side and end walls located wholly within said hospital room and completely enclosing a space independently of the walls thereof, one of said 120 side walls having a doorway adapted to register with said entrance doorway, and the opposite side wall having a correspondingly located doorway, a closure for said last mentioned doorway, comprising hinged-together 125 sections forming a partition and a door,

130

adapted in one position to close off the entire utility room from the hospital room, and in another position to extend transversely between said side walls to convert said utility room into a compartment and a through passage from said entrance doorway into the portion of the hospital room beyond.

4. An article of manufacture for hospital rooms or the like, comprising a top and side walls enclosing a portion of the hospital room independently of the walls thereof and adapted to have toilet fixtures installed in one portion thereof, one of said side walls having an opening to one side of said fixtures adapted to register with the entrance doorway to said hospital room, the opposite side wall having a correspondingly located doorway, hinged wall sections normally closing said last-mentioned doorway and adapted to be swung at right angles to its doorway closing position to close off the fixture containing portion into a separate compartment, and to form a through passage from said entrance into the hospital room, said compartment being accessible from said

passage by a door forming one of said hinged sections.

5. An article of manufacture to be installed in a hospital room or the like, comprising a unitary walled enclosure consisting of top, end and side walls and adapted to be located wholly within said hospital room, one of said side walls having an opening registering with the entrance doorway to said hospital room, a plurality of hinged sections forming a portion of the side wall opposite said entrance and adapted to be swung from a position in the plane of its wall transversely across the enclosed space to form a smaller compartment at one end and a through passage from said entrance into the hospital room at the opposite end, said smaller compartment being accessible from said passageway through a door constituting one of said hinged sections, and a separate door in one of said walls adjacent said compartment for access thereto from said hospital room.

Signed at Evanston, this 5th day of December 1924.

ROGER A. SIMONSON.
